(57) **CLAIM**

The ornamental design of a device for potty training toddlers, substantially as shown in the drawings.

DESCRIPTION

FIG. 1 is a perspective view of a device for potty training toddlers showing my new design;

FIG. 2 is a side elevation view thereof, the opposite side being a mirror image thereof;

FIG. 3 is a top plan view thereof;

FIG. 4 is a front elevation view thereof; and,

FIG. 5 is a rear elevation view thereof.
